UNITED STATES PATENT OFFICE.

DAVID LEMON TOWLER, OF NEWARK, NEW JERSEY.

WHEEL-PULLER.

1,305,322.

Specification of Letters Patent. Patented June 3, 1919.

Application filed May 22, 1918. Serial No. 235,990.

To all whom it may concern:

Be it known that I, DAVID LEMON TOWLER, a citizen of the United States, residing at Newark, in the county of Essex and State 5 of New Jersey, have invented certain new and useful Improvements in Wheel-Pullers; and I do hereby declare the following to be a full, clear, and exact description of the invention, such as will enable others skilled 10 in the art to which it appertains to make and use the same.

My invention relates to improvements in wheel pullers.

An important object of this invention is 15 to provide a wheel puller adapted for use in connection with wheels of different sizes, said wheel puller having adjustable arms adapted to engage the periphery of the wheel at different points.

20 A further object of the invention is to provide a wheel puller arranged on a movable carriage to permit of the easy movement of the device to an operative position, with respect to the wheel.

25 A further object of the invention is to provide a device of the character described, which is expeditious in use, of highly simplified construction and cheap to manufacture.

Other objects and advantages of the invention 30 will be apparent during the course of the following description.

In the accompanying drawings, forming a part of this specification and in which like numerals are employed to designate like 35 parts throughout the same:

Figure 1 is a side elevation of the device, showing the same in an operative position,

Fig. 2 is a central vertical sectional view through the device;

40 Fig. 3 is a fragmentary perspective view of an arm for engaging the lower portion of the wheel,

Fig. 4 is a transverse section, taken on line 4—4 of Fig. 5,

45 Fig. 5 is a front elevation of the device, showing the same applied to a wheel,

Fig. 6 is a plan view of the movable carriage upon which the device is mounted,

50 Fig. 7 is a fragmentary section through a portion of the device, showing the screw for engaging the axle,

Fig. 8 is a central longitudinal sectional view of one of the adjustable arms carried by the device and adapted to engage the lower 55 portion of the wheel,

Fig. 9 is a section, taken on line 9—9 of Fig. 1, and

Fig. 10 is a section, taken on line 10—10 of Fig. 2.

In the drawings, wherein for the purpose 60 of illustration is shown the preferred embodiment of my invention, the numeral 10 designates a U-shaped bracket forming the body portion of the device, said bracket being mounted on a standard 11. A carriage 65 12, having legs 13, which carry rollers 14, is secured to the standard 11 by bolts 15.

An extension 16, formed on one end of the U-shaped bracket 10, is hollow at its outer end for the reception of an adjustable 70 arm 17 curved, as shown, to engage the upper portion of the wheel. A set screw 18, having threaded engagement with the extension 16 on one side thereof, is adapted to engage the arm 17 to hold the same in a 75 set position. Extending from the bottom portion of the U-shaped bracket are outwardly diverging arms 19, having adjustable end portions 20 curved, as shown, to engage the bottom portion of the wheel. Sleeves 22 extending over the arms 19 and 80 the adjustable end portions thereof, carry bolts 23 in threaded engagement therewith and extending through elongated slots in the ends of the arms 19.

As shown in Fig. 2, the bracket 10 is provided with an opening extending longitudinally therethrough and adapted for the reception of a sliding plate 24, having a centrally arranged screw threaded opening 25. 85 An arched support 25' having rigid connection with the bracket 10 extends outwardly therefrom and is provided with a centrally arranged screw threaded opening 26' alining with the screw threaded opening 25 of 90 the plate 24, and is adapted for the reception of a screw 26, having a head 27. As shown, the screw 26 has threaded engagement with the arched support and plate 24 and has its end 28 arranged between the spaced arms 95 of the U-shaped bracket 10. To permit of the screw 26 having its longitudinal axis being brought into alinement with the longitudinal axis of the axle, the plate 24 is adjustable vertically in the bracket 10, and is 100 adapted to be held in a set position by set screws 29. Slots 30 and 31 in the bracket 10 are arranged on opposite sides of the plate 24 and permit of the vertical movement of the screw 26. Elongated openings in the 105 110

outer portion of the bracket 10, designated by the numeral 32, permit of the vertical movement of the arch with the plate 24.

In applying the device to a wheel the arms 5 17 and 20 are engaged with the sides of the wheel, as shown. The screw 26 is now brought into alinement with the axle and by turning the screw, it is obvious that the wheel will be pulled from the axle.

10 While I have shown and described the preferred embodiment of my invention, it is understood that I may make such minor changes in arrangement and construction of parts as will remain within the spirit of the 15 invention and the appended claims.

Having thus described the invention, what I claim is:

1. A wheel puller comprising, a body portion; adjustable arms carried by the body 20 portion and adapted to engage the periphery of the wheel; a plate slidably arranged within the body portion; a screw carried by the plate and having threaded engagement therewith and adapted to engage the end of 25 an axle; and means to hold the plate in a set position.

2. A wheel puller, comprising a U-shaped body portion; an adjustable arm carried by the upper side of the body portion and adapted to engage the upper side of the wheel; outwardly diverging arms carried by the lower portion of the U-shaped body portion and adapted to engage the lower side of the wheel; a vertically disposed plate slidably arranged 30 within the U-shaped body portion; a screw carried by the plate and having threaded engagement therewith and adapted to engage one end of an axle; means to re- 35

tain the plate in an adjusted position; and an arched support carried by the body portion and having threaded engagement with 40 said screw.

3. A wheel puller comprising, a body portion; an adjustable arm carried by the upper side of the body portion and adapted to engage the upper side of the wheel, outwardly diverging adjustable arms carried by the lower portion of the body portion and adapted to engage the lower side of the wheel; a vertically disposed plate slidably arranged 45 within the U-shaped body portion; a screw carried by the plate and having threaded engagement therewith and adapted to engage one end of an axle; and means to retain the 50 plate in adjusted position.

4. A wheel puller comprising a U-shaped body portion, a movable carriage supporting the U-shaped body portion; an adjustable arm carried by the body portion and adapted to engage the upper side of the 55 wheel; outwardly diverging longitudinally adjustable arms carried by the lower portion of the U-shaped body portion and adapted to engage the lower side of the wheel, a vertically disposed plate slidably arranged 60 within the U-shaped body portion; a screw carried by the plate and having threaded engagement therewith and adapted to engage one end of an axle; and means to retain the 65 plate in an adjusted position.

In testimony whereof I affix my signature in presence of two witnesses.

DAVID LEMON TOWLER.
